UNITED STATES PATENT OFFICE.

HENRY BELLON, OF CHICAGO, ILLINOIS.

DIE.

Application filed May 28, 1920. Serial No. 384,853.

To all whom it may concern:

Be it known that I, HENRY BELLON, a citizen of the United States, and a resident of Chicago, in the county of Cook and State 5 of Illinois, have invented certain new and useful Improvements in Dies, of which the following is a specification.

This invention relates to improvements in dies, and more particularly to a die designed 10 and constructed for the making of a particular article of manufacture known as chaplets. To those familiar with the art of metal casting, it is well known that chaplets are used in the molding process for supporting cores within a mold, and especially where open spaces within the finished casting are to be provided for. A familiar example is the cylinder of an internal combustion motor which is cast with an annular 15 chamber surrounding the cylinder, ordinarily known as a "water jacket." Chaplets are manufactured in many shapes and sizes to provide for the many uses to which they are put, and although they are com- 20 paratively simple in their structure and are used in large quantities, it is highly important that they be of uniform dimensions, in order to assure the production of perfect 25 castings.

Heretofore, chaplets have been largely manufactured by hand, which, at the present time, is an expensive and inefficient method, considering the scarcity and high cost of labor, and considering further the 30 large number of these articles that are used. The greatest objection to hand made chaplets is the non-uniformity in dimensions of these articles, and it is a known fact that large users of these chaplets employ a staff 35 of workmen whose entire time is occupied by gauging each lot of chaplets that is received, and sorting and discarding those which do not meet the proper requirements as to size.

The purpose of this invention is to provide a mechanism technically known as a die, which may be used for manufacturing these chaplets by power machinery, and to thereby replace hand labor heretofore employed. The enormous increase in produc- 40 tion, and the corresponding decrease in expense and cost of production go hand in hand with the installation of the power operated machine, and adding to these impor- 45

tant results the absolute uniformity in the 55 finished articles, provides a striking example of the superiority of the device as a labor saving machine, although it is perhaps confined to a particular branch of industry.

The device or die embodying the features 60 of my invention is one especially constructed for the making of a particular form of chaplet, namely, one used in the casting of steam engine or internal combustion motor cylinders, although it is to be understood that 65 with slight modifications a large variety of shapes and sizes may be produced.

In the accompanying drawings, the die 70 for producing the particular type of chaplet hereinbefore disclosed, is set forth in detail, and the description thereof which follows has reference to the several figures which may be briefly described as follows:

Fig. 1 is a view in front elevation of the 75 complete die,

Fig. 2 is a top plan view of the lower or fixed die plate and parts associated therewith,

Fig. 3 is a bottom plan view of the upper or movable die plate, and showing the parts 80 associated therewith,

Fig. 4 is a view in vertical section of the upper die plate taken on line 4—4 of Figure 3,

Fig. 5 is a view in vertical section showing the base of the die at the completion of 85 the forming operation,

Fig. 6 is an enlarged detail view of the forming arbor with parts broken away to show the details of construction, as taken on 90 line 6—6 of Figure 4,

Fig. 7 is a detailed view in longitudinal section showing the parts in the same position as disclosed in Figure 5, and as taken on line 7—7 thereof,

Fig. 8 is a detailed view in cross section as taken on line 8—8 of Figure 2,

Fig. 9 is a detailed view in cross section as taken on line 9—9 of Figure 6, and

Fig. 10 is a perspective view of a chaplet 100 as formed by the die.

The die comprises in general two relatively movable die plates, 1 and 2, adapted to be fixed to corresponding fixed and movable parts of a punch press, or similar power 105 operated machine, so constructed that the movable die plate will travel with reciprocating movement toward and from the fixed

die plate, the complete formation of a single chaplet being accomplished during each stroke of the movable die plate.

Considering first the fixed die plate 1, the same is rigidly secured to a horizontal base plate 3 of the punch press by means of bolts 4-4 extending through endwise opening slots 5-5 formed at the ends of the die plate 1. Located at the central portion of 10 of the die plate 1 is an anvil 6 which rests in an annular recess or depression 7 formed in the upper face of the die plate 1. The anvil projects above the surface of the plate and is provided with a concave surface facing 15 upwardly and forming the bottom surface of the forming recess or depression of the die. On opposite sides of the anvil and arranged longitudinally of the plate 1 are mounted forming blocks 8-8, said blocks 20 being spaced apart at their inner and adjacent ends and are there provided with beveled surfaces 9-9 which terminate above the concave bottom surface of the anvil 6. The upper portion of the beveled surfaces 25 9-9 are convergent and form, as will hereinafter appear, the lateral surfaces or sides of the forming recess. These forming blocks are rectangular in shape, although tapering to some extent at their inner ends, as shown 30 in Figure 2, and furthermore are slidably mounted endwise between longitudinally extending guide rails 11-11, and further provided along their bottom surfaces with a tongue 8^a which rests within a groove 12 35 formed in the surface of the plate 1, as shown in Figure 8. These plates, as before suggested, are movable endwise in a direction toward and from each other, the inward movement being a positive one through 40 the medium of members hereinafter to be set forth, and their rearward movement in the opposite direction being accomplished by the provision of coil springs 13-13 which are partially enclosed within holes extending 45 horizontally from the rear faces of the blocks, the said springs being fixed thereto by means of screws 14-14. The rear or outer ends of the springs are fixed to the plate 1 in a convenient manner at the points 50 15-15.

Extending inwardly from the right hand side of the die plates is a strip feeding guide rail 16, clearly shown in Figures 1 and 2, this guide rail being located in alignment 55 with the anvil 6 as well as the beveled end surfaces 9-9 of the forming blocks 8-8, the inner end of said guide rail terminating immediately above and at the central portion of the right hand forming block 8. As 60 a preferable construction, a plate 17 is interposed between the block 8 and the guide rail 16, said plate being fastened to the block 8 by means of screws, and terminating a short distance rearwardly of the beveled edge 9 65 thereof. The inner end portion of the plate

17 is bifurcated and provides for the attachment of a small spring plate 18 immediately adjacent to the beveled edge 9 of the block. Immediately to the rear of the spring 18 and surrounded by the opening 19 formed 70 in the plate 17 is a transversely extending slot 20 extending through the block 8, as shown in Figure 7. Projecting upwardly through the slot 20 and terminating flush with the surface of the block 8 is a slotted 75 neck portion 21 formed integral with the plate 1, the slot 22 formed within said neck 21 extending vertically downward with a tapered conformation through said plate 1. As will hereinafter be disclosed a cutting 80 blade carried by the upper or movable die plate is adapted to enter the slot formed in said neck 21. Along one side of the guide rail 16 extends a vertical flange 23 which projects beyond the end of the guide rail 85 proper, terminating short of the slotted neck 21 in a transverse portion 23^a projecting outwardly at right angles with the main portion of the flange 23. Extending beneath the transverse portion 23^a of the flange 23 is a 90 flat yieldable plate 24 in alignment with the spring plate 18, the yieldable plate 24 serving as a guiding means for the strips as they are fed from the guide rail 16, beneath the strip cutter hereinafter to be described, and over 95 the forming recess in the fixed die plate 1. Mounted on the transverse portion of the flange 23^a is a vertically extending spring arm 25 adapted to be engaged by the upper or movable die plate 2 in its downward 100 movement, and to exert sufficient pressure upon the strips of material fed to the die, through the medium of the transverse flange portion 23^a, to prevent endwise movement of the strip during the cutting and forming 105 operations.

Referring now to the upper or movable die plate 2, the same is provided at opposite ends with bosses 26-26 in which are mounted downwardly extending guide posts 110 27-27 which engage circular guide openings 28-28 formed in the lower plate 1, these guide posts and openings serving to insure the movement of the upper die plate in a fixed path. Depending from the under 115 side of the upper plate 2, and in vertical alignment with the anvil 6 of the lower plate, 1, is a post 29, carrying at its lower end an arbor 30. This arbor corresponds in shape to the forming recess included between the upwardly facing surface of the anvil 6, and the laterally facing surfaces 9-9 of the blocks 8-8, as clearly shown in Figs. 6 and 7. Referring to Figure 5, it will be seen that the post 29 is 120 extended rearwardly from the anvil 6, and further that a portion of the post immediately above the forming recess is removed, as well as a portion of the arbor 30, so that 125 although the arbor extends the full length 130

of the post, just that portion immediately above the anvil 6 is employed as the forming member, this portion having the form of a laterally extending foot 31, having its upper surface concave as at 31^a (Figure 6), and furthermore, entirely free so that a strip of metal may be bent to completely surround the foot 31. As before suggested, the portion of the post immediately above the foot 31 of the arbor 30 has the form of a vertically extending recess 32, in which is mounted a rotative arm 33 journalled at its upper end by means of a transverse shaft 34 extending through and rearwardly beyond the post 29 and to which the arm is keyed. A small pinion 35 is likewise keyed to the shaft 34 immediately to the rear of the post 29. As clearly shown in Figure 6, the arm 33 is provided at its outer end with a toe 33^a having a convex bottom surface, said toe extending laterally and in a direction of the arbor 30. The arm 33 is adapted to be swung or oscillated from the position shown in Figure 6 downwardly to the position shown in Figure 7; namely, immediately above the foot 31 of the arbor 30, with its bottom surface spaced a short distance therefrom. The arm 33 is swung downwardly or oscillated during the downward movement of the die plate 2, and through the medium of the pinion 35 which engages a vertically arranged rack bar 36 that is mounted upon the fixed plate 1 in such a position that the several rack teeth 37 engage the teeth of the pinion 35 as the latter is carried downwardly into meshing engagement therewith. The function of the oscillating arm 33 will be hereinafter fully disclosed in connection with the description of the manner in which the chaplets are formed.

Referring now more in detail to the arbor 30, the same is preferably connected to the post 29 in a yieldable manner, this being accomplished as shown in Figure 6 by providing the arbor with an integral sleeve 38 which projects upwardly into a downwardly opening bore 39 formed in the end of the post 29. Within the sleeve is mounted a coil spring 40, bearing at its opposite ends against the post and the arbor so as to yieldingly oppose the relative movement of these parts in opposite directions, since manifestly the purpose of this construction is to provide a cushioning effect as the arbor is carried downwardly into contact with the anvil 6 in the fixed plate 1.

At one side of the post 29 and to the right as shown in Figure 1, is a depending arm 41 fixed to the under surface of the plate 2, said arm carrying at its lower end a vertically disposed blade 42 in alignment with the slotted neck 21 of the lower plate 1. This cutting blade 42 is positioned so that when the upper plate is at the upper

extremity of its movement, the lower edge of the blade is completely removed from the slot 22 and at such distance that a strip of material may be fed freely beneath the blade. Located on opposite sides of the central post 29 and extending vertically downward from the plate 2 are two cam members 43-43 having the form of cylindric rods, the lower ends of which extend through circular openings 44-44 formed in the fixed plate 1, and located immediately beyond the rear edges of the blocks 8-8, as clearly shown in Figure 2. The sides of the cylindric cam members 43-43 facing the blocks 8-8 are provided with flattened cam surfaces 45-45 which bear against the blocks 8-8, as clearly shown in Figure 1. At the upper extremity of the cam surfaces 45-45 is formed comparatively short cam surfaces or shoulders 46-46 offset from the surfaces 45-45 a short distance in the direction of the blocks 8-8. As clearly shown in Figures 1 and 7, the sliding blocks 8-8 maintain a separated relationship through the action of the springs 13-13 during that part of the movement of the upper die plate 2 in which the blocks are in contact with the cam surfaces 45-45 of the cylindric cam members 43-43. As the upper plate reaches the end of its downward stroke, however, the blocks engage the cam shoulders 46-46 and are moved inwardly toward each other from the dotted line position shown in Figure 7 to the full line position, this movement, as will be hereinafter pointed out, occurring after the chaplet has been formed by the arbor.

Having described the principal parts of the die, that is to say those parts which accomplish the bending and forming operations, it is thought well at this point to set forth the several operations in forming a single chaplet such as shown in Figure 10, it being understood that the particular type of chaplet illustrated is but one of many different forms that may be made. The material from which the chaplets are formed is preferably fed to the machine in the form of strips of perforated sheet metal of the desired width, these strips being fed laterally along the guide rail 16 and in a direction inwardly from right to left, one margin of the strip bearing against the flange 23 so that the strip passes over the yieldable plate 24 and beneath the transverse portion 23^a of the flange 23.

Assuming that the operation commences with the die at the upper end of its stroke, and the parts in the positions shown in Figure 1, the strip is advanced forwardly until its end engages a shoulder 47 located on the opposite side of the forming recess, and immediately above the forward edge of the left hand block 8, as shown in Fig-

ure 2. The shoulder 47 is preferably formed at the end of a transversely extending arm 48 secured to the upper face of the plate 1 by means of screws 49. Furthermore, the shoulder 47 is slightly elevated from the face of the block 8 to provide a notch 47^a (Fig. 7) into which the forward end of the strip is inserted, thus partially securing the end of the strip as well as limiting the distance that the same may be forwardly advanced. The strip having been properly advanced, immediately before the downward movement of the upper plate 2, commences, is in position to be operated upon. The first operation is accomplished by the cutting blade 42 which severs the end portion of the strip as it passes downwardly into the receiving slot 22. Immediately after this is accomplished, the arbor 30 descends and drives the central portion of the strip downwardly into the forming recesses between the ends of the forming blocks 8—8. The result of this operation is the bending of the strip into U-shape, and the end portion of the strip extending between the forming recess and the severed edge being thrown upwardly into a vertical position. During this initial bending operation, the extreme end portion is drawn from beneath the shoulder 47 and carried downwardly into the forming recess as shown in Figure 7. After the initial forming of the strip into U-shape has been completed, the arm 33 is actuated by the engagement of the pinion 35 with the rack teeth 37 of the rack bar 36, said arm being normally held from rotation and in its upwardly raised position by the provision of a spring pressed plunger 50 engaging a notch formed in the post 29 as clearly shown in Figure 9. The rotation of the pinion 35 swings the arm 33 downwardly, the forward toe portion 33^a striking the upwardly projecting end portion of the strip and bending it laterally and downwardly at right angles against the upper concave surface of the foot portion 31 of the arbor 30, it being noted that the end portion of the strip that has been bent downwardly extends a short distance beyond the opposite end portion now forming one of the side walls of the formed chaplet. The arm 33 comes to rest immediately above the arbor 30 after the bending of the strip completely around said arbor, and while in a position of rest the sliding blocks 8—8 are forced inwardly by the action of the cam shoulders 46—46 which follows immediately after the operation of the arm 33. The effect of the inward movement of the forming blocks 8—8 is to exert pressure upon the side walls of the formed strip or chaplet, with the result that the walls thereof are permanently set so that when the chaplet is removed from the die,

there will be no tendency for the walls of the same to expand or to assume any other shape than that determined by the conformation of the arbor and the forming members surrounding the same.

The inward movement of the forming blocks 8—8 which permanently sets the walls of the chaplets and determines its permanent shape, may be said to be the final operation in the forming process, this step being accomplished at the end of a downward stroke of the die plate 2, which immediately thereafter begins its upward stroke. Manifestly, the forming blocks are released at the instant the cam shoulders 46—46 pass out of contact therewith, thus permitting the springs 13—13 to act, drawing them rearwardly and away from the sides of the arbor 30. Simultaneously the arm 33 is swung upwardly and out of contact with the chaplet by reason of the engagement between the pinion 35 and rack teeth 37, so that the chaplet is free to be removed from the foot 31 of the arbor 30, it being observed that the latter is carried upwardly with the plate 2.

The final operation in forming a complete chaplet is the removal of the same from the arbor 30, this being completed by means of a device known as a stripper, preferably constructed in the following manner:

A stripper sleeve 51 is slidably mounted upon the arbor 30, being held in position thereon by means of a slot and screw connection, as shown at 52 in Figure 3. This sleeve is provided with a rearwardly projecting arm which is fixed to a sliding block 53 mounted upon two parallel guide rods 54 extending horizontally from the post 29. Attached to the rear edge of the lower plate 1 is a vertically arranged cam plate 55 having a cam slot 56 formed thereon. This slot 56 is engaged by a cam roller 57 mounted at the end of an arm 58 mounted upon the block 53. Referring to Figure 5, it will be seen that the cam slot 56 is vertical throughout its lower portion and inclined at an angle of substantially 45 degrees inwardly toward the upper plate 2 throughout its upper portion. Furthermore, the position of the stripper sleeve 51 is to be noted as being withdrawn from that portion of the arbor on which the chaplet is formed; namely, the foot 31 thereof. Assuming now that the upper plate 2 begins its movement in an upward direction, the stripper sleeve 51 will remain stationary until the cam roller 57 engages the inclined portion of the cam slot 56. At this point the sliding block 53 as well as the stripper sleeve 51 are moved forwardly, the latter engaging the chaplet mounted on the arbor, forcing or stripping the same completely therefrom, and allowing it to drop or to be otherwise disposed of in a suitable receptacle. During the downward stroke of the plate 2 the stripper is

manifestly withdrawn from the foot 31 of the arbor 30 by the action of the cam slot 56 where it remains until the succeeding upward stroke.

5 Although the operation of forming a single chaplet is herein described in detail, it is to be understood that the machine is operated continuously so that during each stroke of the upper die plate 2, a complete 10 chaplet is produced.

Although I have described and illustrated a die adapted for producing a particular type of chaplet, it is to be understood that the details of construction may be variously 15 modified for producing other shapes of chaplets without departing from the spirit of the invention. Therefore, I do not wish to be limited except in so far as the invention is specifically set forth in the appended claims.

20 I claim as my invention:

1. In a die of the character described, the combination of fixed and movable die members, one of said die members being provided with a forming recess comprising 25 transversely movable forming blocks, the other of said die members comprising an arbor extending transversely to the path of the movable die member, an oscillating arm mounted on said movable die member, and 30 adjacent said arbor, said members acting successively to bend a strip of metal into U-shape, to bend one end portion thereof over said arbor, and to apply pressure to the formed strip.

35 2. In a die of the character described, the combination of fixed and movable die plates, an arbor mounted on one of said plates and comprising a post having a forming arbor mounted at the end thereof, the other plate 40 having a forming recess formed therein and adapted to co-operate with said arbor to bend a strip of metal substantially into U-shape, and an oscillating arm journaled in said post and operative in the relative movement of the die plates to complete the bending 45 of the strip around said arbor.

3. In a die of the character described, the combination of fixed and movable die plates, a forming recess in one of said plates comprising 50 movable forming blocks, an arbor mounted on the other plate and adapted to fit within said forming recess, and to bend a strip of material into U-shape, an oscillating arm co-operating with said arbor to 55 bend an end portion of said strip over said arbor, and cam members operative subsequent to the bending operations to force said blocks toward each other, thereby setting the bent strip.

60 4. In a die of the character described, the combination of fixed and movable die plates, a forming recess of predetermined shape in

one of said plates and adapted to have a strip of metal advanced over said recess, a forming arbor mounted on the other of said plates in alignment with said recess, and co-operating with said recess to bend a strip of metal substantially into U-shape, an oscillating arm mounted adjacent said arbor, and operative to bend one end portion of the strip transversely and over the arbor, and means for setting the bent strip after the forming operation.

5. In a die of the character described, the combination of fixed and movable die plates, 75 a substantially U-shaped forming recess in one of said plates, comprising slidable forming blocks, an arbor carried by the other plate and adapted to engage said recess, an arm journaled adjacent said arbor, and 80 movable in a direction transverse to the direction of movement of said arbor, and means for actuating said arm comprising a pinion operatively connected therewith, and adapted to engage rack teeth mounted on the 85 first mentioned die plate, and cam members operative in the relative movement of said plates to actuate said blocks toward said recess.

6. In a die of the character described, the 90 combination of fixed and movable die plates, a forming arbor mounted on one of said plates, the other plate having a forming recess therein adapted to co-operate with said arbor to bend a strip of metal into U-shape, 95 an oscillating arm mounted adjacent said arbor, and co-operating therewith in a relative movement of the die plates to bend an end portion of the strip transversely, means for exerting pressure on at least two sides 100 of the bent strip, and a stripper mounted on said arbor and operative to remove the formed strip therefrom.

7. In a die of the character described, the combination of fixed and movable die plates, 105 a substantially U-shaped forming recess in said fixed plate, comprising slidable forming blocks, an arbor carried by said movable plate and adapted to engage said recess, an arm journaled adjacent said arbor, and 110 movable in a direction transverse to the direction of movement of said arbor, and means for actuating said arm comprising a pinion operatively connected therewith, and adapted to engage rack teeth mounted on the first mentioned die plate, cam members 115 mounted on said movable plate and engaging said forming blocks to actuate the same toward said recess after the forming operation, and means for removing the formed 120 strip from said arbor.

In witness whereof, I hereunto subscribe my name this 24 day of May, A. D. 1920.

HENRY BELLON.
